Primary Examiner — Susan E Krakower*Assistant Examiner* — Ramzi Almatrahi(74) *Attorney, Agent, or Firm* — Dahyee Law Group; Leon E. Jew; Rouzbeh Alani(57) **CLAIM**

The ornamental design for a camera, as shown and described.

DESCRIPTION

FIG. 1 is a perspective view of a camera showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines depict portions of a camera in which the design is embodied and form no part of the claimed design.
